[57] CLAIM

The ornamental design for a combined clipper and cap therefor, as shown and described.

DESCRIPTION

FIG. 1 is a perspective view of a combined clipper and cap therefor showing my new design with cap removed;

FIG. 2 is a top plan view thereof;

FIG. 3 is a front elevational view thereof;

FIG. 4 is a right side elevational view thereof;

FIG. 5 is a rear elevational view thereof;

FIG. 6 is a bottom plan view thereof;

FIG. 7 is a top plan view of the design with cap in place;

FIG. 8 is a front elevational view thereof; and

FIG. 9 is a right side elevational view thereof.
